(57) **CLAIM**

The ornamental design for a lumbar device as shown and described.

DESCRIPTION

FIG. 1 is a perspective view of a lumbar device, shown in a condensed configuration;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of the lumbar device of FIG. 1, shown in an extended configuration for clarity of disclosure; and,

FIG. 10 is a left side view thereof.

In the drawings, the dash-dot-dash broken lines depict the surface shading of the lumbar device that form no part of the claimed design.

1 Claim, 10 Drawing Sheets
